LEROY V. ROBBINS, OF BATON ROUGE, LOUISIANA, ASSIGNOR TO STANDARD OIL DEVELOPMENT COMPANY, A CORPORATION OF DELAWARE.

APPARATUS FOR REMOVING COKE FROM STILLS.

Application filed October 18, 1923. Serial No. 669,313.

This invention relates to the art of destructive distillation of hydrocarbons, and will be fully understood from the following description, taken in connection with the accompanying drawing, in which—

Fig. 1 is a plan view partly in section of a still in accordance with the invention, portions being broken away at the ends to show the equipment on the floor;

Fig. 2 is an enlarged sectional view, taken on the line 2—2 of Fig. 1, looking in the direction of the arrow;

Fig. 3 is an enlarged vertical sectional view of the drag along the line III—III of Fig. 1; and

Figs. 4 and 5 are plan and side views respectively of other details, on an enlarged scale.

In the operation of coking-stills the body of residual coke deposited in the still is customarily broken up by hand picks and spuds and is shoveled out. As it is all hand labor and the operatives must work in relay shifts of a few minutes each on account of the heat and working conditions, the labor is both difficult and also very expensive. It has been heretofore proposed to diminish the hand labor required, by preliminarily arranging a chain in parallel coils on the floor of the still so as to be embedded in the coke deposit at the close of the run, and then pull the chain loose, coil after coil, by means of a windlass and donkey-engine. While this accomplished a breaking-up of the coke deposit, the coke all had to be shoveled out and it was found that the coke did not break cleanly from the still surface, and an excessive amount of finishing work was necessary. Later it was proposed to substitute for the chain a series of rectangular open frames connected by short lengths of chain, these being arranged on the floor of the still before the run, and after the run being pulled out serially through a large man-hole at the end. While this broke up the coke and largely removed it, considerable shoveling of stray pieces was required and the frames required special attention to remove blocks of coke stuck in them. An arrangement rendering the cleaning of stills more of a mechanical procedure has accordingly been much desired.

In accordance with the present invention

a still S (see Fig. 1) preferably having a manhole opening entirely across the lower segment of one end is equipped with a series of break-out strips B, these being connected end to end by some flexible means, as swivel links or chain links, and when in operative position being arranged in serial rows across the still floor in the coking area. Each break-out strip is made up of a piece of metal 2 of suitable strength and durable character, for example a piece of boiler plate, and projecting at spaced intervals on each side are lugs or teeth 3 preferably firmly riveted in place. At each end of the strip a hole 4 is provided to receive the links 5 for connecting the strips end to end in series. Fastened to the end of the series of break-out strips by a flexible connection, for instance a chain bridle 6, is a clean-out drag D. While the drag may vary somewhat in construction, it should be strong and yet as light as feasible. Advantageously it may be made up of channel-iron support-runners 6 and a back. The back may be made of one piece of metal if desired, but I prefer to employ an I-beam base 7 shaped to the curvature of the floor of the still and an I-beam straight or chordal top 8 and connecting irons and braces 9, 10 tying the aforesaid members together.

Preliminarily to the run the drag is set on the floor of the still at the back end and the string of break-out elements is arranged row-wise along the bottom of the still, the free end link being placed where it can be at once found after the run. After the distillation run is over, the large end manhole plate is taken off, and the free link at the end of the string of break-out elements is connected to a pull-chain of a suitable donkey-engine windlass or the like, and pulling is started. As the break-out strips one after another are broken loose, the teeth 3 assist by a wedging action, and as the strips are drawn along, the teeth as coke-engaging projections catch the blocks and help to scoop them along out of the still. A slight degree of resiliency in the break-out strip is of advantage in assisting the strip to free itself from the attached coke. Finally the drag is pulled loose in its turn and as it is drawn forward along the entire still bottom it carries along any remaining pieces.

While I have described my invention by reference to certain specific details, it will be understood that changes may be made which come within the spirit and scope of the invention.

I claim:

1. Apparatus of the character described, which comprises a still provided with a man-hole across the lower segment of one end, a closure therefor, a series of flexibly connected break-out strips each having lateral teeth, a drag having support-runners and a back made up of top and bottom I-beam pieces and connecting angle-irons, and a

flexible connection between the drag and the end of the series of break-out strips, said man-hole being large enough to permit passage of the drag therethru.

2. Apparatus of the character described, which comprises a still provided with a man-hole across the lower segment of one end, a series of flexibly connected break-out strips each having lateral teeth, and a drag flexibly connected to the end of the series of break-out strips, said man-hole being large enough to permit passage of the drag therethru.

LEROY V. ROBBINS.
